Primary Examiner — Terry A Wallace(74) *Attorney, Agent, or Firm* — Husch Blackwell LLP(57) **CLAIM**

We claim the ornamental design for a cooler, as shown and described.

DESCRIPTION

FIG. 1 is a perspective view of a cooler according to our new design;

FIG. 2 is a top plan view thereof;

FIG. 3 is a front elevation view thereof;

FIG. 4 is a left side elevation view thereof;

FIG. 5 is a rear elevation view thereof;

FIG. 6 is a right side elevation view thereof; and,

FIG. 7 is a bottom plan view thereof.

Broken lines and the area within the broken lines are for illustrative purposes only and form no part of the claimed design.
